SOLE STITCHING MACHINE

Carmelo Carliano, Buenos Aires, Argentina

Application July 18, 1945, Serial No. 605,784
In Argentina June 14, 1945

3 Claims. (Cl. 112—2)

1

This invention relates to an improved machine for the lateral sewing of the soles of alpargatas or canvas shoes, by means of which several important advantages are secured which will hereinafter more fully be described.

One of the principal advantages attained by the improved machine in accordance with this invention, consists in entirely avoiding any danger of the needle or punch cutting or otherwise damaging the welt, a drawback generally inherent to the known machines actually in use and which is a cause of serious losses amounting to about 14 to 16 per cent of the production manufactured.

Another advantage of the improvements in accordance with this invention consists in that by the use of the same a saving of about 5.76 meters of thread per dozen of canvas shoes is obtained, which multiplied by the number of dozens manufactured per day means quite a valuable amount.

Finally, as a further advantage worthy of consideration it should be noted that by the use of the system of perforating the sole of the canvas shoes performed by the machine in accordance with this invention, a saving of about 50 per cent of the power actually required by the machine operating according to the actual methods is obtained.

The novel machine of this invention also offers several minor convenient features of structure and use which will be referred to in the course of this specification.

All of the several advantages and features above set forth are secured by the particular construction and arrangement of the improved machine of which a preferred embodiment will now be described, by way of example, with reference to the accompanying illustrative drawings, wherein:

Figure 1 shows a side elevation of my improved machine for the lateral sewing of the sole of alpargatas or canvas shoes, which diagrammatically illustrates the means for driving the needle and punches, in accordance with this invention.

Figure 2 illustrates the arrangement of the punches and corresponding needle at the moment of transportation or feeding.

Figure 3 represents the step immediately following the transportation, showing the entrance into the sole of the punch of greatest length.

Figure 4 illustrates a step in direct succession of the foregoing one, during the entrance of the needle and the additional punch fixed to the carrier of the same.

Figure 5 is a view similar to that of Figure 2, in which may be seen the position of the needle

2

and the punch at the moment of starting the feeding movement, after performing a stitching operation.

Figure 6 is a fragmentary front view of the machine, showing the arrangement of the transportation or feeder device and the means for the passage between one sole mold and another, which allow of the feeder device to perform on a double displacement.

10. Figure 7 is an enlarged fragmentary view of the mechanism for releasing the feeder rack, and

Figure 8 illustrates the arrangement of the needle and the additional punch of the same, in the step previous to the passage between two successive molds.

Figure 9 is an elevational view showing the relation of the respective cams and levers actuated thereby.

20. Figure 10 is a view partly in cross section of the front part of the machine showing how the molds are supported.

The same numbers of reference have been used to indicate like or corresponding parts in all the several views.

25. The elements shown by way of example tend to attain, as already stated before, the three basic advantages above referred to.

When observing Figures 2 to 5, it will be noted that, as distinguished from the methods actually in use, the needle 1 is arranged with an additional punch 2, in accordance with the improvements which form the object of this invention, on the same line with and opposite to a punch 3, mounted on the lateral support opposite to a guide member hereinafter to be described.

In a similar way and also as distinguished from the machines actually in use, the operation performed when passing from one mold to the other, does not consist in the present case in interrupting the stitching operation, but by the pressure of the mold, a double linear displacement of the feeder device or rack driving the same is performed.

45. Referring to the drawings and first with particular reference to Figure 1, there is shown in a frame 7, a driving means for the needle 1 and the additional punch 2 mounted in a chuck or carrier 8, and for the punch 3 oppositely aligned

50. with the needle 1 mounted in a chuck or carrier 8'. The chuck or carrier 8' for the punch 3 is mounted on the machine opposite the needle carrier 8. The above referred to driving means comprises a needle operating cam disc 4 keyed to a shaft 4' journalled in bearings 7a and 7b

mounted in the standards or uprights of the frame 1.

The cam 4 is rotated with the shaft 4' by suitable power means, such as an electric motor A and a belt and pulley drive B. Transverse the lower portion of the frame is a bar 7c and pivoted to this bar is an end 6 of a curved lever arm 5. The lever 5 carries a small roller 5a rotatably mounted on a pin extending from the side of the lever 5 adjacent the cam 4 so that the peripheral rims of the rollers 5a and the cam 4 are in frictional engagement. Thus as the cam 4 is rotated its engagement with the roller 5a causes the free end of the lever arm 5 to angularly rock back and forth according to the contours of the cam disc 4.

The free end of the lever 5 is formed into a forked member 5b. The forked member 5b engages a pin 5c extending from the side of the needle carrier 8, in which is secured the needle 1 and the respective additional punch 2. The forked member 5b is thus adapted to convert the angular rocking motion of the lever 5 into a linear motion, with the needle carrier 8 and the needle 1 and punch 2.

The punch 3 mounted in carrier 8' opposite to needle 1 is operated in a synchronous manner with respect to the needle carrier 8 from cam 4 by a lever arm 9 pivoted at one end on a pin 10 mounted in frame 7. The lever arm 9 is connected, above its pivot pin 10 by a link 11 to lever arm 12 pivoted at its lower end on a pin 12a in frame 7, while its upper opposite end mounts a roller 12b for frictional engagement with the periphery of the cam 4 on the opposite side from the friction roller 5a of lever arm 5. The free upper end of the lever arm 9 is connected by a forked member 9a around a pin 9b in a similar manner to the former lever 5, to the slidable chuck 6a, which mounts and carries the punch 3.

From the foregoing description it will be seen that one of the improvements introduced into the machines for the lateral stitching of alpargata soles consists, as already stated, in the alignment of the needle 1 and the corresponding punch 3 of the opposite support, and in the use of an additional punch 2, adapted to simultaneously operate with the needle.

With particular reference to Figure 9, there is mounted, on the end of shaft 4' extended from the exterior of frame 7 a bevel pinion 13' which meshes with a similar pinion 13 mounted on the end of a shaft 14a mounted in suitable brackets, not shown, on each side of the frame 7. The shaft 14a is rotatable from the same power source A and B by transmission of the power through the said pinions, and this shaft 14a has keyed thereto a cam 14, which rotates as shown in Figure 6. As the cam 14 rotates its periphery is positioned so as to frictionally engage with the periphery of a small roller 15, fixed or rotatably mounted on a pin or shaft 16, which pin extends from the side of a pivoted lever 17.

The lever 17 is pivoted to an extension on the lower end of the frame 7 on a pin 17a, while its opposite end is connected by means of a small connecting link 18 to an alternately forwardly and rearwardly slidable feed rack 19. The lever 17 is constantly urged in the direction of the cam 14 by means of a spring 20 anchored at one end to the arm between the roller 15 and the link 18 and at the other end to the frame 7.

Below the rack a release mechanism is provided, consisting of a pivoted swing bar 21, provided on its two ends with studs or contact mem-

bers 22, 22', projecting towards the rack, and on this latter is provided a small projection or stop 23 which during a certain period of the transportation or feeding movement is in engagement with the stud 22.

To the extension of the swing bar carrying the stud 22, one end of a spring 24 is connected which operates to permanently pull the said extension in a downward direction.

Each of the sole carrying molds 24' is provided with a rotatable pawl 25 in engagement with the teeth of the rack 19, for causing the displacement of said molds in continuous succession.

For the better understanding of how at the required moment is performed the double linear displacement of the carrier or feeder rack 19, it should be noted that between the centre of the cam 14 and the points of maximum and minimum distance to the periphery of the same, a difference equivalent to two steps of the rack exists. With reference to the functional aspect of the device shown in Figures 6 to 7, it will readily be seen that the rotation of the cam 4 will cause the rotation of the meshing bevel pinions 13 and 13'. The former pinion, by means of its shaft 4', will rotate the cam 14, which in turn will move the feed rack in the manner now to be described.

When the point of the cam 14 most distant from its centre 14 is in engagement with the roller 15, the assembly will be in the position shown with dotted lines in Figure 6, and in consequence the arm 17 will pull the rack 19 through its connecting rod 18 and thus cause the mold 24' to advance the distance of one tooth. During this time, the swing arm 21 will occupy the position indicated in said Figure 6. While the cam disc 14 continues its rotation, the arm 17 will be retracted to its former position by the action of the spring 20.

When said roller 15 will occupy the point of minimum distance with regard to the centre of the cam 14, the distance which will exist between said cam and said roller will be equivalent to one step of the feed rack. This condition is owing to the fact that, notwithstanding the pull exerted by the spring 20, the arm 17 and in consequence the rack 19, have been unable to complete their displacement, being prevented from doing so by the element 22 which engages with the stop 23.

When the sole will have reached the position shown in Figure 7, which is the step directly following the condition shown in Figure 6, the projection 22' will have been released and in consequence the swing arm 21 will oscillate about its pivot and thus release the stop 23.

At this moment, the arm 17 will extend over the entire distance existing between the roller 15 and the point of minimum distance of the cam 14, which, as has been stated before, is equivalent to two steps of the rack and in consequence as the cam 14 rotates through 180°, the carrier or feeder will perform a motion equivalent to the double of that described, and shown for the position represented in Figure 6.

To make the operation of the feeder and stop mechanism entirely clear it will be stated that the molds are ordinarily moved the distance of one rack tooth by the cam 14 because the arm 22 normally engages the rear edge of the stop member 23 preventing the retraction of the rack. Thus, the cam 14 normally engages the roller 15 only during its cycle of greatest throw. However, when the arm 22 reaches the space between the moulds, the lever 21 rotates under the action

of the spring withdrawing the arm 22 from the path of the stop 23, permitting the rack to move rearwardly under the action of the spring 20 the distance of two rack teeth.

From the foregoing it will be understood that in the period of time elapsed, the repetition of the double displacement just referred to, will depend in all cases of the length of the two molds 24.

With regard to the particular arrangement of the needle 1 and the punch 3 and the addition of a further punch 2, the operation of the device, in accordance with Figures 2 to 5, may be described as follows.

Considering Figure 2 to represent the initial position of the parts, the first movement will correspond with the entrance of the punch 3 which, by passing through the sole, will form the hole by which will penetrate the needle 1. After the punch 3 having completed its stroke in the direction shown, it will commence to recede while simultaneously the needle 1 will advance through said hole, and the additional punch 2 will form an initial orifice.

The needle 1 and the additional punch 2 having performed their entire stroke, both of said members will be retracted, while the punch 3 will remain stationary until the related parts that is, the needle 1, punch 2 and punch 3 will have reached the position shown in Figure 5.

Under these conditions, the feeding of the mold will take place by the distance of one step, as before described and it will be noted that the punch 2 will have performed a small preliminary perforation in the sole, which at the following repetition of the cycle, will be completed by the punch 3.

From the foregoing description it will be seen that owing to the particular arrangement shown, the needle will not perform any perforation, but will only be inserted in a hole already formed. On the other hand, the operation of the punches 2 and 3 will not take place simultaneously, but in an alternate manner and in consequence, the effort to be exerted by the machine, will be reduced to a minimum.

At the same time, the initial perforation performed by the auxiliary punch 2 and afterwards completed by the punch 3, prevents the sole of the alpargata or canvas shoe from becoming fretted, a condition which generally occurs, when using one single punch, at the orifice of issue of the same.

The advantage of the saving of thread, referred to at the commencement of this description, is a consequence of the double stroke of the feeder rack, inasmuch as between the passage of one carrier mould to the other, no stitches are lost and the thread is left with a sufficient degree of tension to allow of the same being conveniently severed by any suitable device provided for that purpose in the machine.

With regard to the percentage of failure, or tear of the welt at the end of the shoe by the action of the punch or the needle, it will be clearly seen when observing Figure 8, that the punch will never perforate the ends of the sole.

Having thus clearly shown the advantages obtained by the use of the improvements above described, it should be understood that several modifications might be introduced in the arrangement shown and described, without departing from the scope of the invention as set forth in the following claims.

Having now particularly described and ascer-

tained the nature of my said invention and in what manner the same is to be performed, I declare that what I claim and desire to secure by Letters Patent, is:

1. A machine for stitching the soles of canvas shoes or the like comprising a frame, guide means supported on the top of the frame, molds movably mounted in the guide, feeder means for moving said molds step-by-step from one end of the frame to the other, said molds being formed to hold the uppers and soles of a canvas shoe in proper position for stitching, a needle carrier mounted on the said frame transverse the said mold guide, a needle mounted in said carrier having associated integrally therewith an auxiliary punch, a second punch, a punch carrier oppositely positioned across said guide from said needle carrier, power means for said machine, a drive shaft connected to said power means, a driven shaft, a gear transmission operatively connecting said shafts for rotation, a cam disc carried by the driven shaft, a lever actuated by said cam for driving said mold feeder means, and means actuated by the pressure of one of the molds for causing a double alternate linear displacement of the feeder movable into the guide passage between molds, whereby an alternate punching and sewing operation is provided.
2. A machine for the stitching of soles of canvas shoes or the like comprising a frame, guide means supported on the top of the frame, molds movably mounted in the guide, feeder means for moving said molds step-by-step from one end of the frame to the other, said molds being formed to hold the uppers and soles of a canvas shoe in proper position for stitching, a needle carrier mounted on the said frame transverse the said mold guide, a needle mounted in said carrier having associated integrally therewith an auxiliary punch, a second punch, a punch carrier oppositely positioned across said guide from said needle carrier, power means for said machine, a drive shaft connected to said power means, a driven shaft, a bevel gear secured to an end of said drive shaft, a similar bevel gear secured to an end of said driven shaft, said gears being in mesh, a cam mounted on said drive shaft, a second cam mounted on said drive shaft, said first cam being adapted to actuate said needle carrier and said punch carrier with an alternate punching and sewing operation, said second cam being adapted to actuate said feeder means, said feeder comprising a mold feed rack, said rack being driven by said cam so as to feed said molds forward step-by-step along said guide, and a swing arm having upwardly projecting ends laterally with respect to said rack through the bottom of said guide means, to thereby limit the movements of said rack and the movement of said molds according to the alternate actuation of said needle and punch carriers.
3. A machine for the stitching of soles of canvas shoes or the like comprising a frame, guide means supported on the top of the frame, molds movably mounted in the guide, feeder means for moving said molds step-by-step from one end of the frame to the other, said molds being formed to hold the uppers and soles of a canvas shoe in proper position for stitching, a needle carrier mounted on the said frame transverse the said mold guide, a needle mounted in said carrier having associated integrally therewith an auxiliary punch, a second punch, a punch carrier oppositely positioned across said guide from said

needle carrier, power means for said machine, a drive shaft connected to said power means, a driven shaft, a bevel gear secured to an end of said drive shaft, a similar bevel gear secured to an end of said driven shaft, said gears being in mesh, a cam mounted on said drive shaft, a second cam mounted on said driven shaft, said first cam being adapted to actuate said needle carrier and said punch carrier with an alternate punching and sewing operation, said second cam being adapted to actuate said feeder means, said feeder comprising a mold feed rack, said rack being driven by said cam so as to feed said molds forward step-by-step along said guide, a swing arm having upwardly projecting ends laterally with respect to said rack through the bottom of said guide means, to thereby limit the movements of said rack and the movement of said molds according to the alternate actuation of said needle and punch carriers, a stop extending from a side of said rack, said sewing arm being centrally pivoted intermediate its ends to said frame below said guide, one of its projecting ends serving as a stop for the feeding motion of said rack when moved upward into the guide by pressure of one of the molds on the other of said ends, and a spring adapted to normally urge

said stop end upwardly and pull down on said stop engaging end according to the position of the low and high points of said second cam and said molds to release the stop, whereby said rack is given a motion of one step at the low part of said second cam and of two steps of the rack at the high point of said cam as it rotates, to properly feed said molds in synchronism with the alternate movements of said needle and auxiliary punch carrier and said oppositely positioned punch carrier.
